FURNACE-CHARGING DEVICE

Frank L. Tocher, Morris Plains, N.J., and Mitchel Kleinman, Brooklyn, N.Y., assignors to M. H. Treadwell Company, Inc., New York, N.Y., a corporation of New York

Filed June 14, 1962, Ser. No. 202,621

8 Claims. (Cl. 214—18)

This invention relates to a device which is useful, for example, in efficiently and economically handling scrap metal and other solid material and in charging such materials into a furnace or converter in which metal is to undergo refining. It relates, more particularly, to such a device which is suitable for charging such materials into a furnace or converter having an upwardly opening charging mouth for receiving material from elongate containers having an endwise discharging chute or opening, the terms "furnace" and "converter" being interchangeably used herein. Such converters have come into use in connection with oxygen processing of molten iron into steel. One type of such converter is disclosed, for example, in United States Patent No. 3,013,789, dated December 19, 1961.

An important object of this invention is the provision of a device which may handle scrap or other solid materials more efficiently and may charge such materials into a converter more rapidly than means heretofore provided for similar purposes. Such rapid charging is important, not merely in consideration of charging alone, but reduction of the duration of a charging operation minimizes heat losses from the converter during charging of the latter.

Another important object of this invention is the provision of a solid-materials handling device of such character that it operates very efficiently and economically with related plant equipment presently in use, thereby acquiring increased production from such present equipment.

Another important object of this invention is the provision of a solid-materials charging device which may be shifted readily from place to place within a steel plant by existing crane equipment and which has plural material containers and means for dumping them sequentially into a converter very rapidly to achieve much faster converter charging than hitherto.

Another important object of this invention is the provision of an improved solid-materials handling device which may coact with a crane beam to be held stable while being moved from place to place by the crane in a plant.

This invention is described herein, for convenience, as utilized in the processing of molten iron into steel, without, however, limiting the invention to such use. Also, such solid-materials containers are hereinafter referred to, for convenience, merely as "boxes" or "scrap boxes."

The mentioned and other more or less obvious objects are achieved by a device, according to this invention, which, referring only to the broader features thereof, comprises a frame which may rest on a floor or other generally horizontal surface and has a stud or equivalent means engageable by a crane hook or the like by which the frame may be lifted from the floor. The base is provided with an upright column having means at its upper end engageable with a horizontal surface, usually an undersurface of a crane beam, to stabilize the device when it is being moved by the crane. Also, pivoted on the base are plural boxes, and means associated with the column for tilting said boxes separately to dump their contents into a converter. The crane or equivalent means may serve to shift the frame as needed to bring the several boxes sequentially into charging position in relation to the converter.

2

A preferred embodiment of this invention is illustrated in the accompanying drawings in which:

FIGURE 1 is an elevational view of the furnace-charging device, as fully lifted by a related crane, looking at the discharging ends of three similar scrap boxes in the device, and showing the latter as used without doors on said boxes.

FIG. 2 is a vertical sectional view substantially on the line 2—2 of FIG. 1, but showing a door such as may be used on the boxes.

FIG. 3 is a detail view shown in vertical section substantially on the line 3—3 of FIG. 2.

This invention may best be understood by reference to FIG. 2 wherein is shown a rigid frame comprising a horizontal base 10, upright columns 12, a motor platform 14, supported on the base by one or more upright support members 16 (only one being shown) reinforced by rigid struts 18 and 20, and upright tackle-engaging brackets 22. All the mentioned parts of the frame are suitably interconnected, as illustrated, as by riveting and/or welding.

As shown in FIG. 1, the base 10 is of such substantial width as to accommodate three scrap boxes 24 thereon in side-by-side spaced relationship and may rest in a very stable condition upon a floor surface or the like. The columns 12, each advantageously comprising a pair of uprights 12a and 12b, are rigidly interconnected at their top ends by a cross-beam 26, and toward each end of the latter is provided an inverted trolley consisting of a pair of rollers 28 working on axles 30 extending between bracket plates 32 fixed to the beam 26. These rollers, as hereinafter explained, are in rolling engagement with the underside of crane beams 34, when the device is fully elevated, to stabilize the frame during certain movements and operations thereof.

The scrap boxes 24, as illustrated, are alike and of generally semi-cylindrical shape. Each of these boxes has upright bracket plates 36 welded or otherwise suitably fixed thereto toward opposite sides and toward the front or mouth ends thereof and these plates, at lower extremities thereof, are pivoted at 38 to longitudinal beams 40 which constitute parts of the base 10. This pivotal mounting enables the boxes 24 to be pivoted between a normal horizontal position and a tilted discharging position as shown in full and broken lines respectively in FIG. 2. At its rear end, each box 24 is provided with an integral rigid bracket 42 serving as a foot for supporting the box in a horizontal position upon the base 10.

The back end of each box is closed by a fixed back wall 44, and the front end of each box may be open or, if desired, may be provided with a door 46 hinged to the top of the box at 48 and may be held closed against the bottom of the box by a suitable latch 50.

Means for tilting each box forwardly to discharge its contents by gravity are associated with related column 12, and comprise a draft member in the form of a pair of sprocket chains 52, 52a working on sprockets 54, 54a, 56 and 56a. The sprockets 54, 54a are keyed upon a common shaft 58, suitably borne in the upper ends of uprights 12a and 12b and driven through transmission means illustrated as comprising a sprocket type drive chain 59 working on a driven sprocket 60 keyed upon the output shaft 64 of a speed reducer 66 which is driven by a suitable, reversible motor 68 through a drive-shaft connection 70. The motor and speed reducer are mounted upon the platform 14, and the motor may be controlled from a crane cab or from some other suitable location. The sprockets 56 and 56a are rotatable with or about a shaft 72 suitably carried in the base 10; and suitable means (not shown) may be provided for shifting the shaft 72

vertically to enable the tension of the chains 52, 52a to be tightened to the proper extent.

The two chains 52, 52a are unified by a box-like link 74 (best shown in FIG. 3) within which two rollers 76 are mounted for free rotation upon stub shafts 78; these rollers being so spaced as to accommodate between them, preferably with an accurate fit, a lug in the form of an arcuate tongue 80 which is rigid with the bracket 42 forming the foot at the rear of the box 24. When the motor 68 is operated to cause the link 74 to rise, the tongue 80 is drawn upwardly while sliding within said link, causing the box 24 to be tilted as indicated in broken lines in FIG. 2. The tongue 80 is formed with a stop lug 82 at its free end to assure against the tongue becoming disassociated from the link 74.

The device, as illustrated, is shown with three boxes although it could be employed with as few as two boxes or with more than three boxes. It preferably has two tackle-engaging brackets 22 each having a sturdy hook-engaging stud 84 carried by and between two plates 86, of said brackets, which plates are spaced sufficiently to accommodate a crane hook between them and about said stud. The studs 84 are above the center of gravity of the device either in its loaded or unloaded condition.

As is well understood by those familiar with this art, an overhead, traveling crane, of a character commonly used in steel and other plants, comprises a pair of spaced beam members, such as indicated at 34, arranged at their ends to ride along elevated crane-way track members (not shown). These beam members provide tracks for a tackle-trolley (also not shown) which may move along said beam members, transversely of the crane-way. The tackle-trolley carries means for uniformly taking up and paying out separate cables 88 in unison. These cables work in separate sheave blocks 90 each of which carries a pivotally suspended hook 92.

Suitable shield plates 98 may be provided on the columns 12, between the latter and the boxes 24 to protect said columns and the chains 52, 52a from damage during use of the device; these plates having vertical slots 100 to accommodate the vertically movable tongues 80.

By reason of the uniform operation of the cables in unison, the hooks 92 remain in substantially unchanging interrelationship. The hooks are applied to the two studs 84 which are spaced substantially similarly to the spacing between the two cables so that, when the crane lifts the device, the latter is effectively held against material oscillation about a vertical axis.

The device normally rests in a substantially horizontal position upon a floor or equivalent surface (not shown), to receive scrap and/or other solid materials in the plural boxes 24 to fill the latter, the doors 46 (if such doors are provided), meanwhile, being latched closed.

An overhead crane then moves into position above the device and the crane's hooks 92 are lowered and positioned in lifting relation to the studs 84. Then, the crane lifts the device to bring and hold the rollers 28 firmly against the flat undersurfaces of the crane's two beams 34, thereby stabilizing the device against material swinging.

While thus held stable, the device is moved by the crane to a position above and toward one side of a converter into which the contents of the several boxes 24 are to be charged. Then, the crane lowers the device to approximately its relationship indicated in FIG. 2, to the mouth 94 of a fragmentarily shown converter 96, the crane and the device carried thereby being shifted to the extent necessary to bring one of the boxes 24, preferably an end box, into proper charging juxtaposition to the converter's mouth.

Then, after release of latch 50, the motor 68, related to that one box, is operated to cause the chain 52 to raise the rear end of that box and cause the latter's

contents to gravitate through the mouth 94 into the converter 96. Then, the motor 68 is reversely operated to restore the empty box to horizontal position, its door again held closed by the latch 50.

The other boxes, seriatim, are shifted by the crane into charging relation to the converter, are discharged thereinto and restored to their horizontal attitudes in the manner described. After all boxes have been emptied, the device is preferably again lifted to stabilized engagement with the crane beams 34 and carried back to a station at which the device is again employed for charging purposes in the manner described. It will be understood that converter charging, as just described, is much more rapid than if boxes of the greatest practical size are separately carried to a converter for charging scrap into the latter.

In FIG. 2, the charging device is illustrated, for convenience, as being in stabilized engagement with crane beam 34 and also in charging position in relation to the converter 96. Some plants may be so arranged that said two relationships are coexistent; however, the described converter charging can be satisfactorily performed by the disclosed apparatus even after the device has been lowered to some extent by the crane, as hereinbefore explained.

The provision of separate motors 68 for tilting the boxes 24 is a convenient arrangement, but it will be realized that an alternative arrangement could employ a single motor and separately operable clutches drivingly connecting the motor selectively to the chains or equivalent means of the several boxes.

It should be obvious that the concepts disclosed herein may be employed in various other ways without, however, departing from the invention as set forth in the following claims.

We claim:

1. A furnace-charging device comprising a liftable frame adapted to rest on a generally horizontal surface and having lifting-lug means adapted for engagement by independent lifting means to enable the frame to be lifted from said surface, plural boxes separately pivoted to said frame for pivotal movement in a vertical plane, and separate tilting means for each of said boxes, carried by said frame and coacting separately with said boxes to pivot and thereby tilt the latter, said tilting means comprising, for each of said boxes, an upright column constituting a part of said frame, a movable endless chain carried by said column, and plural wheels, mounted for rotation on said frame, coacting with said chain to guide the latter in a fixed course of linear movement, one of said wheels being located at an upper portion of said column and a lifting portion of said chain extending substantially vertically to said one wheel and having a lifting link; the tilting means further comprising a lifting tongue rigidly integral with a related box and extending rearwardly thereof into lifting engagement with said link, and a motor operatively connected to said chain to linearly move the latter.

2. A furnace-charging device according to claim 1, said lifting link having an opening through which said lifting tongue extends and in which said tongue is movable during linear movement of said chain.

3. A furnace-charging device according to claim 2, said tongue having a lug on its free end adapted to abut said lifting link to oppose disassociation of said tongue from said link.

4. A furnace-charging device comprising a liftable frame adapted to rest on a generally horizontal surface and having lifting-lug means adapted for engagement by independent lifting means to enable the frame to be lifted from said surface, plural boxes separately pivoted to said frame for pivotal movement in a vertical plane, separate tilting means for each of said boxes, carried by said frame and coacting separately with said boxes to pivot and thereby tilt the latter, and a motor carried by said frame, and said tilting means, for each of said boxes, comprising a

lifting tongue, rigid with said box and projecting rearwardly therefrom, upright column means rigid with said frame, a draft member guided within said column means in sliding, tilting engagement with said tongue, and extending upwardly therefrom into moving engagement with an upper portion of said column means, and transmission means operatively arranged between said motor, on the one hand, and upper portions of said column means and said draft member, on the other hand, and adapted to move said draft member upwardly to tilt the related box.

5. A furnace-charging device comprising a liftable frame adapted to rest on a generally horizontal surface and having lifting-lug means adapted for engagement by independent lifting means to enable the frame to be lifted from said surface, plural boxes separately pivoted to said frame for pivotal movement in a vertical plane, separate tilting means for each of said boxes, carried by said frame and coacting separately with said boxes to pivot and thereby tilt the latter, and a motor carried by said frame, and said tilting means, for each of said boxes, comprising a lifting tongue, rigid with said box and projecting rearwardly therefrom, upright column means rigid with said frame, a draft member guided within said column means in sliding, tilting engagement with said tongue and extending upwardly therefrom into moving engagement with an upper portion of said column means, and transmission means operatively arranged between said motor, on the one hand, and upper portions of said column means and said draft member, on the other hand, and adapted to move said draft member upwardly to tilt the related box, 30 said device further comprising steadyng means, toward the upper end of said column and wider than the latter, adapted to maintain firm steadyng contact with an adjacent non-vertically movable horizontal surface when the device is in an elevated position, whereby to oppose 35 material swaying of the device.

6. A furnace-charging device according to claim 5, said steadyng means comprising a pair of rollers enabling the device to be moved horizontally while held in said steadyng contact with said horizontal surface.

7. A furnace-charging device according to claim 5, further comprising, in combination, a crane beam having a flat horizontal undersurface, the latter constituting the mentioned non-vertically movable surface, and vertically movable crane-hook means; said hook means being engageable with the device above the latter's center of gravity to lift the device sufficiently to establish and maintain said firm steadyng contact of said steadyng means with said undersurface.
- 10 8. A combination according to claim 7, wherein said boxes are in side-by-side relationship, said lifting-lug means comprise a pair of spaced lifting lugs on said frame toward one end of the latter and at a first line normal to said boxes, said column means are disposed rearwardly of said boxes toward the opposite end of the frame and, at upper end portions, extend transversely of said boxes, said steadyng means being provided on said column means at two spaced points at a second line substantially parallel to said first line, the combination including a spaced pair of said crane beams separately contactable with said steadyng means at said two spaced points, and a spaced pair of said crane hooks separately engageable with said lifting lugs, whereby to lift and steady said device without material turning of the device about a vertical axis.
